EDWIN W. STONE, OF LONGMEADOW, MASSACHUSETTS, ASSIGNOR TO BIGELOW-HARTFORD CARPET COMPANY, OF THOMPSONVILLE, CONNECTICUT, A CORPORATION OF MASSACHUSETTS

PILE-FABRIC LOOM

Application filed March 22, 1929. Serial No. 349,206.

This invention relates to pile fabric looms for the production of a pile surface, either cut or uncut, and is more particularly directed to pile wire controlling mechanism.

It is now the ordinary practice in looms of the above type to provide a carriage, or horse, as it is sometimes called, for the withdrawal of the front pile wire from the fabric or cloth and insert such pile wire into the open shed. The pile wire carriage is now usually given its pile wire withdrawing and inserting movements by means of a continuously moving chain and an intermittently moving and actuated rope or cable connected to the carriage. The withdrawal of the pile wires from the cloth requires considerably more power than the insertion of the withdrawn wire into the shed, and to meet this condition the continuously moving chain is utilized for the pile wire withdrawing motion, while the rope or cable is utilized for the pile wire inserting motion.

During the withdrawal of a pile wire from the cloth the rope operating mechanism is idle and it is withdrawn outwardly with the carriage by a pull on the rope or cable which tends to stretch it. This stretch is particularly observable where the loom is of increased width incident to the demand that has arisen during recent years for wider and wider carpets and rugs and the like, and since the pile wire supporting switch occupies a front position during the withdrawal movement of a pile wire, and a rearward position for the insertion of that pile wire into the shed, the inner end portion of the switch and the wire carried by it is liable to strike the head or butt end portions of the wires in the cloth as the switch is moved from its front towards its rear position. This condition is incident to the stretch that is imparted to the rope or cable as the pile wire is withdrawn, so that the retractile force of the rope or cable acts upon the pile wire carriage to move it inward slightly as soon as the carriage has been tripped from the pile wire withdrawing chain, and the wider the loom and consequent length of the rope or cable, the more emphasized will this retractile force of the rope and inward movement of the carriage

become as soon as the carriage is released from the chain.

An important feature of the present invention consists of means for holding the pile wire carriage in its outer withdrawn position against the retractile force of the rope or cable when the carriage is released or tripped from its connection with the withdrawing chain, and since the purpose of the carriage holding means is to prevent engagement of the inner end of the withdrawn pile wire with the heads or butts of the wires in the cloth, as it and the switch are moved to pile wire inserting position, said holding means is placed under control of switch movement, the construction being such that the carriage is released from the holding means by movement of the switch to its rearward or pile wire inserting position.

It is the common practice to provide means for tripping the carriage or horse from the chain when the former has reached its outer position, and such tripping instrumentalities work effectively to this end except under occasional conditions when the carriage may fail to be released from the chain. Should this occur, the carriage will continue to move outwardly with the chain, contact with the tripping devices, and in its continued outward movement cause severe breakage of parts. Another feature of the present invention therefore consists in mounting the tripping devices so that upon unusual strain placed thereon the tripping devices themselves will be detached from the support on which they are mounted, and they, along with the pile wire carriage, will move to the outer end of the support and drop therefrom without breakage.

The invention and novel features thereof will best be made clear from the following description and the accompanying drawings of one good form thereof.

In the drawings:

Fig. 1 is a front general elevation of portions of a pile fabric loom and pile wire controlling mechanism containing the present invention;

Fig. 2 is a general plan view showing the switch in pile wire inserting position;

Fig. 3 is a detached detail showing the position of the switch and catch when the former is moved to its pile wire inserting position;

Fig. 4 is a general perspective view at the outer end of the carriage support, showing the general relation of parts as the carriage is being moved to its outer position;

Fig. 5 is an enlarged section on the line 5—5 of Fig. 1;

Fig. 6 is a sectional front elevation of the pile wire carriage tripping means and chain;

Fig. 7 is a plan view with parts broken away and showing a modified form of the switch controlled catch for the pile wire carriage;

Fig. 8 is an enlarged side elevation showing the modified form of the switch controlled catch; and

Fig. 9 is a section on the line 8—8 of Fig. 8.

In the general views shown in front and plan by Figs. 1 and 2 the loom frame proper comprises the usual side frames 1, lay 2 and shuttle boxes 3, one at each side of the loom, and extending laterally from the side frame 25 of the loom and rigidly secured in place is the pile wire carriage supporting frame 4 having a suitable guideway 5 for the pile wire carriage 6. Mounted in the lower part of the guideway 5 is the pile wire withdrawing chain 7 which passes about the sprocket wheel 8 at the outer end of the supporting frame and around a similar sprocket wheel 9 at the inner end of the supporting frame. The pile wire withdrawing chain 7 is continuously driven from the chain wheel 10 which as shown is formed as a sprocket wheel for engaging the lengths of the chain to impart continuous and positive movements to the chain to cause the run in the guideway to move outwardly, and secured to the chain 7 is a projection or lug 11, of which there may be any suitable number, for engaging a part on the pile wire carriage as will presently appear. As usual, the chain 7 passes about suitable guide rolls 12 on the supporting frame.

As hereinbefore noted, the purpose of the chain 7 is to withdraw the front pile wire of the group from the cloth, and the pile wire inserting means as shown comprises the rope or cable 13, one end of which is secured to the pile wire carriage 6, at 14, and from the pile wire carriage the rope extends inwardly and passes about a guide pulley 15 at the inner end of the supporting frame and then about the rope wheel 16 which may be intermittently driven, as usual, from any suitable source of power, but as shown in the present instance of the invention it is driven from the motor 17 and a train of gearing 18 to impart through 60 the rope wheel the initial or inserting movement to the carriage and then the rope wheel is freed from its driving means, as usual, to permit the pile wire withdrawing chain to function and withdraw the pile wire from the cloth. The rope wheel as shown is of the

scroll type whereby a suitable speed regulation of the carriage in the pile wire inserting movement may be effected. The parts so far described are of usual construction and need no further elucidation, as they are well understood in the art.

The pile wire carriage 6 is provided with a pile wire withdrawing hook 19, as indicated more clearly in Fig. 4, and is likewise, as usual, provided with a pile wire pusher to insert the pile wire in the shed, but since these details may be of any preferred construction their further description appears unnecessary.

The pile wire carriage shown on an enlarged scale by Fig. 6 comprises the guide members 20 which engage the guide grooves formed in the upper part of the supporting frame, as usual, and pivotally mounted upon the carriage 6 at 21 is the lever 22 having a hooked end portion 23 for engagement with a projection 11 on the pile wire withdrawing chain 7. It is essential that the connection between the pile wire withdrawing chain and the pile wire carriage shall not become detached during pile wire withdrawing movement, and as a means to this end the pile wire carriage has pivotally connected thereto at 24 the locking lever 25, the lower end of which is adapted to engage a recess 26 in the hook member 22 when the latter is in its operative connection with the chain. A spring 27 normally imparts to the locking lever 25 its locking movement and this may be supplemented also by the leaf spring 28, the construction being such that when the carriage is at the inner end of its travel the hook member 22 may engage the projection 11 on the pile wire withdrawing chain, whereupon the end of the locking lever will be moved by the described springs into its locking position to maintain the parts in engagement.

When the pile wire carriage has been moved to its outer position it is essential that the connection between the carriage and the chain be interrupted, and as a means to this end the present invention provides a bracket 29 at the outer end of the supporting frame 4, and adjustably secured to the bracket 29 which is normally in fixed position at the outer end of the supporting frame is a trip device for the locking lever 25, which consists in the present instance of a roller 30 mounted upon a stud 31 and adjustably secured in position in a slot 32 of the bracket 29, the construction being such that as the carriage moves to its outer position the locking lever 25 will be tripped from its locking position, thereby freeing the part 22 for disengagement from the chain. To insure such disengagement, the pivoted member 22 has an upwardly extending arm 33 adapted to strike a trip device 34 adjustably mounted on the bracket 29, as indicated in Fig. 6. The construction is

such that as the carriage moves to its outer pile wire withdrawing position the locking lever 25 is first trapped, then the member 22 is positively lifted from engagement with the pile wire withdrawing chain. So far as the present invention is concerned, the parts described may be variously contrived, the essentials being that the carriage may be freed from the chain when it reaches its outer position.

Pivotaly mounted upon a bracket 35 extending from the supporting frame is the switch 36, its pivotal connection with the bracket 35 being shown in Fig. 3 by the pin 15 or bolt 37. The switch 36 has the pile wire supporting groove 38 which is engaged by a pile wire as the latter is withdrawn from the cloth and is guided thereby during the inserting movement of the pile wire into the 20 shed.

As hereinbefore stated, the switch is moved into two positions, one the pile wire withdrawing position, and after the pile wire is withdrawn the switch is moved to its pile 25 wire inserting position, as shown more clearly by Fig. 2. Suitable means are employed for imparting such movements towards and from the front of the loom, and is herein typified as a link 39 which may be appropriately 30 driven, as usual, from some going part of the loom.

When the switch 36 is moved from its front or pile wire withdrawing position to its rear or pile wire inserting position, the pile wire 35 then in the guide or groove of the switch is swung rearwardly, as indicated by the dotted lines *a* Fig. 2, past the heads or butt end portions of the pile wires then bound in the cloth, as indicated at *b*, so that it becomes essential 40 during such movement of the switch that the pile wire being swung to its rearward inserting position shall not strike the heads or butts of the pile wires then in the cloth.

As hereinbefore stated, however, the pile 45 wires are withdrawn from the cloth by the chain 7, and likewise the rope 13 and the scroll about which it passes are moved by the pull of the chain, so that the carriage travels to its outer position while placing stress upon 50 the rope or cable. Such stress causes an initial stretch of the cable or rope and when the carriage has reached its outer position and is tripped from its connection with the chain, as hereinbefore described, the pile wire carriage 55 is apt to be moved inwardly by the retractile force of the stretched rope or cable, a condition which would cause the end of the pile wire then in the switch to strike the heads or butts of the pile wires then bound in the 60 cloth as the switch is moved from its front pile wire withdrawing position to its rear or pile wire inserting position. This condition is augmented where the loom is of extra width as now demanded by the trade for the 65 production of increased widths of carpets,

rugs and the like, and one of the main purposes of the present invention is to obviate this defective condition of operation by providing a catch to hold the pile wire carriage in its outer position when released from connection with the chain and to continue such hold upon the carriage until by movement of the switch towards pile wire inserting position the holding means is tripped.

In the construction represented by Figs. 75 3, 4 and 5, the switch 36 has an outwardly extending portion 40 on which is mounted a catch for engagement with a projection on the pile wire carriage when the latter has reached its full outward movement.

Mounted upon the carriage 6 is an abutment or shoulder 41 adapted to be engaged by the latch 42 when the carriage is at its outward limit of movement, such catch being mounted as shown in Figs. 3, 4 and 5 upon the extended portion 40 of the switch. The catch may be variously contrived but as illustrated in the present instance of the invention it comprises a latch carrying bracket 43 secured to the extension 40 of the switch, 80 and pivotally mounted on the bracket 43 at 44 is the catch 42, the lower end portion of which is bevelled, as at 45, so that as the abutment 41 on the carriage passes outwardly it will lift the catch and finally the latter will 85 drop in front of the abutment 41 to thereby hold the carriage in its outer limit of movement.

The catch 42 has a projecting portion 46 which extends into the bracket 43, and connected to the portion 46 of the catch is a rod 47 which extends upwardly through the upper member of the bracket 43 and is under the influence of a spring 48 normally tending to hold the catch in its carriage locking position. If desired, the tension of the spring and its effect upon the catch may be varied by the adjusting screw 49 threaded to the upper end portion of the rod 47.

When the carriage is given its pile wire 100 withdrawing movement by the chain the switch is in its front position, that is, the inner end of the switch is moved into position to have the front pile wire of the group in the cloth withdrawn in the guide groove 38 of the switch, and as the pile wire carriage is moved outwardly by the chain in withdrawing the pile wire, the catch 42 is in position to engage the shoulder or projection 41 on the carriage and thereby hold the carriage 105 in its outer position when released from the chain, to prevent the retractile force of the rope or cable from moving the carriage inwardly.

When the switch is moved or swung from 110 its pile wire withdrawing position to its rearward or pile wire inserting position, as indicated in Fig. 2, the catch 42 which has been described as mounted upon the member 40 of the switch, will be swung into full line 115 120 125 130

position, Fig. 3, to thereby carry its holding portion from the line of movement of the shoulder or abutment 41 on the carriage, so that when the switch is moved to its pile wire inserting position the catch is tripped, to thereby free the carriage to its pile wire inserting movement.

From the construction described as one embodiment of the present invention it will be noted that the catch is controlled in its releasing movement of the carriage by the movement of the switch to its rearward or pile wire inserting position, a condition which insures proper movement of the end of the pile wire about to be inserted in the shed past the butts or heads of the pile wires then bound in the cloth.

In the modified construction illustrated in Figs. 7, 8 and 9, the catch for holding the pile wire carriage in its outer position when released from the chain, is pivotally mounted upon its support at 50 and the catch 51 has a holding shoulder 52 which is adapted to engage a complementary shoulder on a lug 53 mounted on the pile wire carriage. In this construction the catch 51 is normally under the influence of a spring tending to place the parts 52 and 53 in operative position, but yieldable, nevertheless, to permit the part 53 on the carriage to move under the holding end of the catch. One good form of spring means to this end consists of a spring 54 surrounding a pin 55 passed through the idle end 56 of the catch, and adjustment of the spring tension may be effected by the nuts 57, as indicated in Fig. 8.

Extending downwardly from the catch 51 is the finger 58 which rests upon the horizontal arm 59 of a bell crank lever pivoted at 60 to the supporting frame 4 or at one side thereof, as indicated in Fig. 7. The downwardly extending end 61 of the bell crank is connected at 62 to a rod 63 which is under control of the switch.

As indicated in Fig. 7, the switch 36 is pivotally supported at 37 upon the bracket 35, as previously described, and extended laterally and secured to the outer end of the switch is an arm 64 to which is secured the inner end of the rod or link 63, the construction being such that when the carriage reaches its outer position on the pile wire withdrawing movement, the arm 64 will move the link or rod 63 in a direction to rotate the bell crank pivoted at 60 so that the catch may engage the projection 53 on the carriage. When, however, the switch is moved rearwardly into its pile wire inserting position, the arm 64 acting as a crank will move the rod 63 in the reverse direction, thereby turning the bell crank so that it acts through the finger 58 to release or trip the catch from its holding relation with the carriage.

It appears, therefore, that in both the preferred and modified forms of the invention

with respect to the catch for holding the carriage in its outer position against the retractile force of the stretched rope or cable, the catch is automatically tripped to release the carriage by swinging movement of the switch into its pile wire inserting or rearward position.

It may happen at times through improper operation of the mechanical parts for releasing the carriage from the chain when the former reaches its outward position that the carriage remains in engagement with the chain, a condition which obviously means breakage of parts by the continued outward movement of the carriage beyond its normal limit. To obviate this objectionable operation and breakage of parts, the bracket 29 is secured to the supporting frame 4 by give-way connections which may permit the bracket 29 to be released from its holding means so that the bracket and the pile wire carriage may move with the chain beyond the pile wire carriage limit without breaking any of the parts which when they reach the full outer position of the chain run may drop from the supporting frame.

As one good means to this end the bracket 29 is secured to the supporting frame by shearable pins 65 which are normally of sufficient stability to effect release of the chain and pile wire carriage without rupture, but when the carriage remains in operative engagement with the chain and is consequently moved beyond its outer limit, such shearable pins will break before any injury is done to other parts of the mechanism, thereby permitting the bracket 29 and the carriage and their operating devices to be returned into operative position merely by the employment or addition of new shearable pins.

The construction described as one good practical form of the present invention may obviously be varied in structural details, the essentials in this respect being that the carriage may be held in its outer position by the catch in opposition to the retractile force of the cable or rope and be released only upon and in response to movement of the switch to pile wire inserting position, and while the shearable pins or bolts 65 furnish a simple and effective means for the prevention of breakage when the carriage fails to be released from the chain, it will be apparent that other equivalent means may be employed.

What is claimed is:

1. In a pile fabric loom, the combination of a pile wire carriage supported for movements to withdraw and insert pile wires, a pile wire supporting switch movable to one position for withdrawal of a pile wire from the cloth and to another position for insertion of a pile wire in the shed, mechanisms for moving the pile wire carriage to withdraw and insert pile wires, means for holding the pile wire carriage in its outer re-

tracted position when released from the wire withdrawing mechanism, and means actuated by movement of the switch towards pile wire inserting position to release the carriage to its pile wire inserting movement.

5 2. In a pile fabric loom, the combination of a pile wire carriage supported for movements to withdraw and insert pile wires, a pile wire supporting switch movable to one position for withdrawal of a pile wire from the cloth and to another position for insertion of a pile wire in the shed, mechanisms for moving the pile wire carriage to withdraw and insert pile wires, a catch for holding the pile wire carriage in its outer retracted position when released from the withdrawing mechanism, and connections between the catch and switch actuated by movement of the switch towards pile wire inserting position for releasing the pile wire carriage to its wire inserting movement.

10 3. In a loom employing pile wires, in combination, a pile wire carriage supported for reciprocatory movement to insert and withdraw pile wires, a pile wire supporting switch adapted to occupy one position during the insertion of a wire and a different position during the withdrawal of a wire, means for moving the carriage in the wire withdrawing direction, a rope for moving the carriage in the wire inserting direction, means for holding the carriage in its withdrawn position against the tension of the rope, and means controlled by movement of the switch to wire inserting position for releasing the carriage from the holding means that a wire may be inserted in the shed.

15 4. In a pile fabric loom, the combination of a pile wire carriage mounted for movements to insert and withdraw pile wires, a chain for imparting pile wire withdrawing movement to the carriage, a rope connected to the pile wire carriage for imparting pile wire inserting movement thereto, a pile wire switch movable to and from position for inserting a pile wire in the shed, a catch for holding the pile wire carriage in its outer position against the retractile force of the rope when the carriage is released from the chain, and means controlled by the switch for freeing the carriage from the catch by movement of the switch towards pile wire inserting position.

20 5. In a pile fabric loom, the combination of a pile wire carriage, a pile wire supporting switch movable to one position for withdrawal of a pile wire from the cloth and to another position for the insertion of a pile wire in the shed, mechanisms for moving the pile wire carriage to withdraw and insert pile wires, a catch adapted to engage and hold the pile wire carriage in its outer position when released from the withdrawing mechanism, and means actuated by movement of the switch towards its wire insert-

ing position for releasing the carriage to its wire inserting movement.

25 6. In a pile fabric loom, the combination of a pile wire carriage, a chain for moving the carriage to withdraw pile wires from the cloth, a rope or cable for moving the carriage to insert pile wires in the shed, a pile wire supporting switch pivotally mounted for movement towards and from pile wire inserting position, a catch for holding the pile wire carriage in its outer position against the retractile force of the rope or cable when the carriage is released from the chain, and connections between the switch and catch actuated by pivotal movement of the switch towards its wire inserting position for tripping the catch and freeing the carriage to its pile wire inserting movement.

30 7. In a loom employing pile wires, in combination, a pile wire carriage supported for reciprocatory movement to insert and withdraw pile wires, a pile wire supporting switch pivotally mounted and adapted to occupy one position during the insertion of a wire and a different position during the withdrawal of a wire, mechanism for reciprocating the carriage, and a latch carried by the switch and adapted to be shifted by pivotal movement of the switch into and out of position to hold the carriage retracted.

35 In testimony whereof, I have signed my name to this specification.

EDWIN W. STONE.
